UNITED STATES PATENT OFFICE.

WILLIAM J. GIOVANNETTI, OF BROOKLYN, NEW YORK.

FOUNTAIN PEN.

Application filed March 31, 1925. Serial No. 19,660.

To all whom it may concern:

Be it known that I, WILLIAM J. GIOVANNETTI, a citizen of the United States, and a resident of the city of New York, borough 5 of Brooklyn, in the county of Kings and State of New York, have invented a new and Improved Fountain Pen, of which the following is a full, clear, and exact description.

10 This invention relates to a fountain pen. An object of the invention is to provide a simple and efficient fountain pen adapted to enable a person to write in ink of a plurality of colors.

15 Another object concerns the provision of a simple and efficient construction whereby the pen is divided up into a plurality of sections which are readily interchangeable and removable from each other.

20 A further object concerns the provision of simple and efficient means whereby the various sections of the pen can be quickly and easily clamped together.

The invention is illustrated in the drawings, of which—

Figure 1 is a side elevation of the pen;

Fig. 2 is an elevation with portions in section;

Fig. 3 is a section on the line 3—3 of Fig. 2; and

Fig. 4 is a perspective view of one section of the pen.

The form of the invention shown in the drawings is a preferred form, although it is understood that modifications in the construction and arrangement of the parts and in the character of the materials used may be adopted without departing from the spirit of the invention as set forth in the appended claims.

40 In its general aspect, the invention comprises a pen made of at least two parts which are slidably engageable one with the other. Each of these sections is provided with a pen and an ink reservoir and is preferably adapted to supply a different colored ink. The sections are provided with means for slidably engaging each other and with means for holding them in their proper relation when engaged.

45 In the preferred form of the invention is

shown a pen made in two halves 10 and 11 provided with a button 12 on one half and a groove 13 on the other adapted to engage slidably to permit the abutment of the sections so as to form the appearance of a complete single unit. The sections are provided with pens 14 and 15 and at their other ends with similarly threaded projections 16 and 17. On each section adjacent the pen portions are threaded portions 18 and 19 adapted when the sections are engaged to be alined. The threaded stems 16 and 17 when alined, as shown in Fig. 2, can be engaged by the threaded portion of a cap 20, preferably in the form of a tapered portion having a pencil or lead device 21 at the end thereof.

55 The other end of the pen is engageable by a cap 22 which is adapted to engage the threads 18 and 19 when they are alined.

60 The sections are provided with slots 23 and 24 through or in which means can be disposed for the purpose of filling the pen by manipulating the rubber bag ordinarily disposed in pens of the self-filling type. In order to fill the pens, the caps 20 and 22 can be removed and the sections can be slidably disengaged so that each section can be 65 filled separately with the desired color of ink.

70 What I claim is:—

1. A fountain pen, which comprises a plurality of separate independent semi-circular sections each having a pen and a reservoir, and means permitting the slidable engagement of one section with the other to form a complete circular whole.

75 2. A fountain pen, which comprises a plurality of separate independent semi-circular sections each having a pen and a reservoir, means permitting the slidable engagement of one section with the other to form a complete circular whole, and means adapted to lock the sections together when thus engaged.

80 3. A fountain pen which comprises two semi-circular half sections each provided with a pen and a reservoir, threaded portions on each half section adapted to be alined when the half sections are engaged to 85 form a complete circular whole, and means 90

on each section for engaging with the other sections to hold them together.

4. A fountain pen which comprises a pair of sections having semicircular cross-section, each section being provided with a pen and a reservoir, the threaded portions on the end of each section adapted to be alined to form

a complete threaded end when the sections are engaged, a tongue on one of said sections, the other of said sections having a 10 groove engaged by said tongue, and a cap adapted to engage the threaded portions when alined to hold the sections together.

WILLIAM J. GIOVANNETTI.
